HOLLAND N. STEVENSON, OF PELHAM, NEW YORK

SURGICAL INSTRUMENT

Application filed September 5, 1929. Serial No. 390,601.

- This invention relates to an improved instrument for operations on thin osseous tissue in interior body portions inaccessible for open operation and particularly for nose operations. In operations on the interior nose passages it is frequently necessary for the removal of diseased matter to get access to infected cavities which lie near these interior passages and are separated from them by osseous partitions. The usual practice, up to the present time, in sinus trouble for example, has been to first pierce or prick such partitions by means of a pricking tool and then widen the prick-hole with cutting instruments. This operating method is objectionable for several reasons. The change from one instrument to others causes delay of the operation which for surgical and other reasons should be performed as quickly as feasible. The hole made by the primary pricking tool is small and provides a poor start for the ensuing cutting actions. Such thin bony tissue is very liable to tear and bend away in the widening operation of the primary hole, a condition which is frequently aggravated by an infection of the bone and periosteum itself resulting in a swollen or softened condition so that there is a strong tendency of such portions to avoid the action of a blade or some similar operating tool and to resist any attempts of quickly removing them. For these reasons it is almost impossible in most cases to provide a clear-cut opening in such walls; at all events, it requires much skill and effort and time, and renders the draining and cleaning of such cavities very wearisome and not always perfectly reliable.
- In order to overcome these deficiencies of the hitherto employed procedure I have conceived a new instrument which is to be used as a combined piercing and punching tool. The object of the invention is to provide a tool for operations of the kind stated before which allows the operator in quick succession to first prick a hole in a comparatively thin bony wall and then widen it by an action of substantially punching nature without leaving indentations or loose fringes. By this tool the operator may form either the finally desired opening or provide one to serve as a wide enough primary hole for the further removal of wall portions by other instruments. The latter or additional removal of wall portions is greatly facilitated by the sufficient and clean-cut nature of the original opening made by my tool.
- In the following detailed description of the instrument reference will be had to the accompanying drawing.
- Fig. 1 is a side elevation of the completely assembled instrument in one operating size, comprising the frame, the outer operating handles, the intermediate connecting portions, and the operating tool proper;
- Figs. 1^a and 1^b represent detached details of Fig. 1;
- Fig. 2 is an enlarged cross-section on line 2—2 of Fig. 1;
- Fig. 3 is an enlarged longitudinal cross section of the operating tool proper;
- Fig. 4 is a side elevation of the detached operating blade;
- Fig. 5 is a transverse cross-section of this blade on line 5—5 of Fig. 4;
- Fig. 6 is a top plan view of the frame end portion with the blade removed;
- Fig. 7 is a transverse cross-section through the frame end portion substantially on line 7—7 of Fig. 6; and
- Fig. 8 is a transverse cross-section through the same on line 8—8 of Fig. 6.
- As will be noted from Fig. 1, the instrument as shown in its preferred form is composed of four parts or elements which are movably linked with each other. The frame with its handle 1, thumb grip 2, intermediate sheath portion 7, and terminal portion 10 gives the necessary rigid support for the remaining parts, which are the operating handle 20 with finger grip 22, the operating rod 30, and the operating blade 40.
- The terminal portion 10 and part of the sheath and rod adjacent to it are so shaped that they can be introduced into the nostril of a patient. The instrument may be manipulated by swinging the operating handle 20 about its fulcrum 3 on the frame, reciprocating movements may be imparted to the operating rod 30 through the pivot pin 24 which,

in turn, cause corresponding opening and closing movements of the blade 40 about its pivot 9 with respect to the blade-receiving frame portion 10, so that this portion and the blade may be said to form a shears-like tool. 5 To start the operation, the instrument is inserted and brought in the right position with the blade closed. After the blade has been opened (for instance to a position as shown in Fig. 1), the prick hole is made by using the frame as a handle for depressing the pointed end of the blade.

10 Before describing the particulars of the blade, its coacting frame portion and the further cooperation of these parts, some other details of construction will be pointed out.

15 The screw 4 in the frame provides an adjustable stop position for the projection 21 of the operating handle and thereby for the handle 20 itself, and makes it possible to so adjust the instrument that the blade 40 is in a desired angular relation to the axis of the operating rod 30 when the two handles are held in extreme straddling position (this 20 blade position need not necessarily be the right angle position as shown in Fig. 1).

25 The operating handle 20 (see Fig. 1^a) terminates in two prongs 23 which hold the pin 24 between them. The end of the operating rod engages this pin by means of a slot so that a sliding pivot connection between the rod and the handle is obtained.

30 In order to hold the rod down in its guide or sheath 7, a head screw 31 (see also Fig. 1^b) attached to the rod slidably engages a slot 5 of the frame. The slot terminates in a wider end portion 6 which, for disassembling and cleaning purposes, permits the screw head to pass through.

35 Fig. 2 shows how the rod is supported in the intermediate or sheath portion 7 of the frame.

40 The blade mating frame portion 10 (see Figs. 3, 6, 7 and 8) may be made integral with the frame or jointed to it by welding, soldering, or in some other suitable manner. It forms a centrally apertured, tapering frame end portion with transversal wall 45 at 11 and side walls 12, which latter are circularly extended upwardly at 13 and then gradually fall off to the contour of the sheath.

45 The upwardly extending portions 13 carry two concentrically situated pins 15 attached to them by riveting or in some other way. These pins form the bearings for the blade 40 (see Figs. 3, 4 and 5). The bearing portion 41 of the blade is provided with two lateral notches 42 which engage the pins 15 as pivots. A centrally located notch 43 on this bearing portion permits the ball-shaped end 50 of the operating rod 30 to freely turn the blade about its pivots. The bearing portion extends in the spoon-shaped blade portion which comprises a bottom 48 tapering in the pointed end 44 and two upwardly curved 55 marginal portions 45. The contour of these

side portions near the pivotal end of the blade substantially conforms to the circular shape of the enlarged side walls 13 of the frame end. These upstanding marginal portions have edges formed with sharpened teeth at 60 the pivotal end 47 and on intermediate portions 46 as well.

65 It will be understood now that the blade and its companion frame end portion will coact much in the fashion of a die and a matrix. The companion frame 10 conforms closely to the contour of the blade so that the outer edges of the blade all along the portions 44, 45, 46, and 47 cooperate with the corresponding inner edges of the frame as shearing edges that define a punching area. In other words, after the primary prick hole has been made with the blade in its upstanding position, as shown in Fig. 3, the surgeon closes the operating handles and thereby 70 moves the blade towards the frame in closing position with the effect that a portion of the bony wall corresponding to the inner area of the frame aperture is punched out. The severed tissue will be received and held 75 within the frame walls, and its easy and safe removal is thus secured.

80 The operation and advantage of my instrument ought now to be clear to one skilled in the art from the foregoing description. 85 The instrument disclosed is the first one known to me that is constructed both for originally piercing the osseous tissue (of the nose for example, in making a drain for the sinus cavity) and for punching an opening 90 in the wall. Ordinarily, one instrument is inserted for the piercing of the wall and then one or more are successively inserted to make the opening. By changing instruments the 95 surgeon has lost exact registration or contact with the tissue and in actual practice this has led to a lot of difficulty. But with the new instrument the original wall piercing action is accomplished by blade 40, and the same 100 blade will still be in the best possible contact 105 and position and without delay is then swung down on frame 10 to punch an opening in the wall. An opening punched in this way ordinarily has sharper and better defined walls than can be uniformly produced by any other 110 method or skill that I know about. With a clean hole of the nature described, the drain from the sinus cavity may frequently be sufficient without any enlargement. But often 115 enlargement is necessary. When it is, the ordinary punching instruments may be used, as known by the surgeon, and with better effect because he can proceed with swiftness and certainty that he has only a clean-cut hole to enlarge. In the old practice much time and 120 skill has been consumed in trying to make certain that the enlarged hole was not made by a bending back of the walls without cutting them. The osseous tissue of the nose has 125 been extremely difficult to work upon, on ac- 130

count of its tendency to move away from the instruments and later move back and partially close the opening. Of course the almost inaccessible position and the difficulty of knowing the exact nature of the work done by instruments heretofore used presented one of the problems of this invention. I have found from observation of actual cases that it is extremely important to make certain of a clean-cut opening through the sinus cavity wall and with such a start the proper draining of the cavity is greatly simplified. That is one definite objective of prime importance as a feature of the present invention.

In order to facilitate the severing of these portions and to assist the punching effect of the instrument, I prefer to provide the saw-like indentations or teeth, which render the action quite reliable by a combination of punching and cutting effect.

Another definite feature of my invention, though of somewhat lesser importance, is the principle of mechanical linkage that I have employed throughout in the assembly of the instrument. All the fulcrums of the instrument consist of pivot elements that can freely be slid in and out of engagement with their bearing element in a transverse direction with respect to the pivotal axis; while, as long as the instrument is in its operative positions, there is no danger of separation of the various elements. The same principle is applied to the rod and sheath member. This type of kinematic linkage has two great advantages in the surgical art. Fulcrums, for instance, consisting of a pivot and a cylindrical bearing surface of axially sliding engagement, represent by their very nature favorable conditions for the development of germs. A thorough cleaning of such portions is difficult and unreliable. With my construction, which is free from slit-like cavities and easily accessible for a thorough cleaning action in all its links, the danger of infection is minimized.

The disassembling is performed by turning the handles in adjacent position, in which position the operating rod can be taken out of its pivot engagement at 24, due to the freedom, in this position, of the screw 31 to pass through the slot opening 6. By swinging the disengaged rod end out of the sheath, the ball end 32 of the rod will gradually also disengage its notch 43 on the blade, with the result that, then, all parts are free to be disassembled. The assembly is carried out in the reverse order with the same ease.

The description, as well as the figures, refer to an embodiment of the invention preferred at the present time; however, there may be made changes in the construction without departing from the spirit of the invention, and in this respect I wish to be lim-

ited by the claims rather than by the description and drawing.

What I claim is:

1. A surgical instrument for making an opening in thin osseous partitions located in body portions inaccessible for open operation, comprising a small body-insertable, shears-like tool operated by corresponding movements of a pair of larger scissor handles connected to the tool by relatively movable, body-insertable connecting links, one of the members of said shears-like tool being pointed for individually producing with open shears a primary hole by piercing action, and both members having mating marginal portions with shearing edges defining a punch hole area for jointly enlarging, by closing the shears subsequent to the piercing action, said primary hole by an action of substantially punching nature.

2. A surgical instrument for making an opening in osseous partitions adjacent the interior nose passages, comprising a frame for holding and inserting the instrument in the nose, an operating handle movable with respect to the frame, and an intermediate connecting element movable relative to the intermediate frame portion for transmitting rotary movements to the inserted operating end, said operating end comprising a frame end portion for the support and the reception of the bone parts to be removed, and a blade, rotatable relative to said frame end portion, having a pointed end for a primary independent piercing action and marginal portions defining a punching area for a secondary punching action in cooperation with the mating edges of the frame end portion.

3. A surgical instrument for making an opening in osseous partitions adjacent the interior nose passages, comprising a frame for holding and inserting the instrument in the nose, an operating handle movable with respect to the frame, and an intermediate connecting element movable relative to the intermediate frame portion for transmitting rotary movements to the inserted operating end, said operating end comprising an apertured tapering frame end portion for the support on and the reception between its marginal walls of the bone parts to be removed, and a sharp-ended blade conforming to said inner marginal walls and rotatable relative to them so as to be adapted to be held either angularly to them for an independent primary piercing action or to be received between them in a secondary punching action.

4. A surgical instrument for making an opening in osseous partitions adjacent the interior nose passages comprising a frame for holding and inserting the instrument in the nose, an operating handle movable with respect to the frame, and an intermediate connecting element movable relative to the in-

- 24
1. A surgical instrument for transmitting rotary movements to the inserted operating end, said operating end comprising an apertured tapering frame end portion for the support on and the reception between its marginal walls of the bone parts to be removed and a pointed, spoon-shaped blade, rotatable relative to said frame end portion, with upstanding and part of their length indented marginal portions, for this blade to act as a primary piercing tool in a position angular to the frame end and as a secondary combined punching and cutting tool in cooperation with the inner edges of said marginal walls of the frame.
2. A surgical instrument for making an opening in osseous partitions adjacent the interior nose passages comprising a frame for holding and inserting the instrument in the nose, an operating handle movable with respect to the frame, and an intermediate connecting element movable relative to the intermediate frame portion for transmitting rotary movements to the inserted operating end, said operating end comprising a tapering, apertured frame end portion with lateral walls for pivotally receiving between them, at portions concentrically enlarged on one side with respect to the pivotal axis, a blade in punching relation, which blade has a generally spoon-shaped form with sharply pointed tip and with upstanding marginal portions whose edges near the pivotal end substantially conform to the edges of said concentrically enlarged frame portions and are provided at this end with sharpened teeth which also extend over part of its intermediate edge portions, for said blade to act as a primary piercing tool in angular position to the frame end and as a secondary combined punching and cutting tool in cooperation with the corresponding edges of said lateral walls of the frame end.
3. A surgical instrument for making an opening in thin osseous partitions located in body portions inaccessible for open operation, comprising a small body-insertable, shears-like tool operated by corresponding movements of a pair of larger scissor handles connected to the tool by relatively movable, body-insertable connecting links, all of said various elements having kinematic links of such construction as to permit their assembling and disassembling in transverse direction to their respective kinematic axis without the aid of separate joining elements, one of the members of said shears-like tool being pointed for individually producing with open shears a primary hole by piercing action, and both members having mating marginal portions with shearing edges defining a punch hole area for jointly enlarging, by closing the shears subsequent to the piercing action, said primary hole by an action of substantially punching nature.
4. A surgical instrument for sinus operations and the like including a shearing tool having two relatively movable shearing members, one member having pivotal stud means, the other member having a hub bearing with a segment cut out so as to permit the latter member at its hub part to be hooked on said stud means in position for pivotal movement between the two members, an operating rod for the pivoted hub member having an extension for slidably engagement with an open radial slot in the hub member, said hub member having such a radial slot located at such an angle that the operating rod extension holds the pivoted members in operating relation so long as said extension is in said slot and means to reciprocate the operating rod in a straight line to cause one shearing member to pivot on the other through the operating connection between the extension of said rod and the hub bearing.
5. The combination of claim 4 with a guide sheath extending from one of the tool members for the operating rod and a stud and slot means to prevent relative tipping movements within the range of the tool members' normal operation and to permit such movement at a point beyond such range.
6. A surgical instrument for making an opening in thin osseous partitions in body portions inaccessible for open operation, comprising a tool with a part for first punching through such a partition and with a mating part for then receiving the first part with a shearing action to remove a portion of the partition for the desired opening, said tool being operable first to punch and then to shear without change of operating position except in the movement of the tool parts, by which movement the punching step carries both tool parts into the right position for the shearing step and the latter can follow without any delay for instrument adjustment between the steps of such an operation, and means for manipulating said tool parts from a sufficient distance to reach an accessible position for the surgeon's hand.
7. A surgical instrument for sinus operations and the like including a shearing tool having two relatively movable shearing members, one member having pivotal stud means, the other member having a hub bearing with a segment cut out so as to permit the latter member at its hub part to be hooked on said stud means in position for pivotal movement between the two members, an operating rod for the pivoted hub member having an extension for slidably engagement with an open radial slot in the hub member, said hub member having such a radial slot located at such an angle that the operating rod extension holds the pivoted members in operating relation so long as said extension is in said slot and means to reciprocate the operating rod in a straight line to cause one shearing mem-

ber to pivot on the other through the operating connection between the extension of said rod and the hub bearing, with a guide sheath extending from one of the tool members for the operating rod and a stud and slot means to prevent relative tipping movements within the range of the tool members' normal operation and to permit such movement at a point beyond such range, and a handle member for said sheath, said handle member having a stud support, a second handle member having a hook-shaped recess to hang on the stud support for pivotal movement, said second handle member having a hook-shaped connection with the rear end of the operating rod separable by lifting the latter handle member away from its support on the first named handle member, all constructed and arranged so that all parts of the surgical instrument can be quickly disassembled for cleaning purposes by unhooking such parts.

In testimony whereof I have affixed my signature.
